Atty.

UNITED STATES PATENT OFFICE.

SAME PATERNO, OF MILFORD, MASSACHUSETTS.

MECHANICAL TOY.

1,216,353.

Specification of Letters Patent. Patented Feb. 20, 1917.

Application filed February 1, 1916. Serial No. 75,585.

To all whom it may concern:

Be it known that I, SAME PATERNO, a citizen of the United States, residing at Milford, county of Worcester, State of Massachusetts, have invented an Improvement in Mechanical Toys, of which the following description, in connection with the accompanying drawing, is a specification, like characters on the drawing representing like parts.

10 This invention relates to an improvement in mechanical toys.

An object of this invention is the construction of a novel toy structure which provides platforms movable at the will of 15 the operator and upon which platforms are positioned representations of various objects and figures more or less fanciful and pleasing.

Another object is to construct such a mechanical toy that it may be readily assembled 20 and demounted affording opportunity for some elemental training of the young in primary mechanical movements and to afford ease in packing and shipment and in replacement and repair of any injured parts.

25 Other objects of the invention will more fully appear from the following description and the accompanying drawings and will be pointed out in the annexed claims.

30 In the drawings,

Figure 1 is an elevation of the assembled toy;

Fig. 2 is a detail view partly in section of the platform actuating apparatus;

35 Fig. 3 is a view of one of the uprights;

Fig. 4 is a section of one of the platforms;

Fig. 5 is a view of the crown;

Fig. 6 is a view of one of the crown bars.

40 In this selected embodiment of the invention there are disposed two platforms which are rotatably supported. To augment the fanciful effect of this device, the platforms are preferably rotatably actuatable in opposite directions. The turning post may consist of a single integral rod but herein it consists of several sections suitably joined to function as a single member. The shaft 1 is supported in the base 2 of the box-like casing 3,

45 the top 4 of which is suitably apertured to clear the shaft. The lower end of the shaft 1, which as shown is preferably tapered, is rotatably mounted in the base 2 by means of a bearing offered by means of a substantially centrally projecting boss 5 of the base. The shaft 1, adjacent its lower bearing end, has

mounted loosely thereon a sleeve 6. Any suitable means may be provided for the actuation in opposite directions of the shaft and its sleeve but for this purpose there are 60 employed the relatively inexpensive stamped spur gears of the usual type where a relatively small amount of power is to be transmitted. The spur 7 is fixed to the actuating shaft 8 journaled in the bracket 9 secured to 65 the top 4 and base 2 of the casing by means of screws 10. The outer end of this actuating shaft is offset and has secured thereto a handle 11 for the convenient manual operation of the device. The spur 7 meshes with 70 the similar spurs 12 and 13. The spur 12 is affixed to the shaft 1 and functions, upon its actuation, to revolve the shaft 1. The spur 13 is affixed to the sleeve 6 and obviously revolves it in the reverse direction. The lower 75 platform 14 is suitably apertured to receive therethrough the shaft 1 and is positioned upon the annular shoulder 15 formed on the upper end of the sleeve 6. This platform 14 is suitably secured to the sleeve 6 and is rev- 80 oluble therewith. The upper platform 17 is carried by the shaft 1, being supported preferably by means of a pin inserted in the aperture 18 of the shaft 1. The upper platform 17 is thus revoluble with the shaft 85 1 while the lower is revoluble in the reverse direction with the sleeve 6. Preferably, the central apertures of the respective platforms are each provided with a downwardly projecting annular shoulder 25 as shown on the 90 platform 14 in Fig. 4. Representations of figures and various objects are placed upon the revoluble platforms, a few fanciful objects being shown in the drawings herein, while the edges of the two platforms shown 95 are given a decorative effect.

The upper portion of the shaft may be journaled in any suitable manner, but, in this embodiment, is preferably afforded a bearing member carried by the upper frame 100 of this device. The uprights, preferably four, form the supporting structure of the frame of the upper portion of the toy.

The lower portions 19 of the uprights 105 form reinforcing corner posts for the four corners of the lower casing. The upper portions 20 of the uprights preferably are given a decorative shape to attain a fanciful effect in the assembled toy. The cross bars 21 are of novel configuration and are suitably 110 secured to the squared upper end portions of the uprights. The crown bars 22 pref-

erably radiate from the bearing member or crown 23. Each of the lower ends of these crown bars is constructed to effect a mortised joint with the top of one of the respective uprights, while each of the upper ends of these crown bars 22 is preferably constructed to effect a mortised joint with the crown 23. The upper end of each of the bars 22 is apertured to correspond to an aperture in the crown wherein may be received a pin, screw or similar instrumentality. This crown is suitably centrally apertured to receive and to afford an upper bearing for the shaft 1. These crown bars, similarly to the cross-bars and uprights, are preferably fancifully ornamented so that the whole frame-work achieves a decorated effect. Herein, the crown is provided with four apertures in each of which the end of a fanciful cord is retained. Each cord has secured thereto objects representing leaves while the lower end thereof, passed through an aperture in the lower end of the crown bar, has secured thereto a depending fanciful object. In this embodiment of the invention the upper end portion of the shaft 1 is vertically apertured to receive in snug engagement therein the end of a short stem 24 which enters an aperture in the end portion of a mast-head member, a selected embodiment of which is shown bearing the letters "U. S. A."

This mechanical toy is of relatively few parts, is simple in assemblage, inexpensively manufactured and can be produced to be sold at a small cost. It is durable and is pleasing and amusing in operation.

It is to be understood that the construction disclosed herein is illustrative but not restrictive and that various modifications may be made within the spirit and scope of the claims annexed hereto.

Having fully described my invention what I claim as new and desire to secure by Letters Patent is:

1. A toy comprising a rotatable shaft, said

shaft comprising a plurality of complementary demountable sections, object-bearing means demountably carried by and rotatable with one of said sections, a sleeve demountably positioned on one of said sections and revoluble independently thereof, object-bearing means demountably carried on said sleeve and rotatable therewith, and means for rotating said sleeve and said sectional shaft in opposite directions. 50

2. A toy comprising a base, an upwardly projecting frame, a rotatable shaft, said shaft comprising a plurality of complementary demountable sections, object-bearing means demountably carried by and rotatable with one of said sections, a sleeve demountably positioned on one of said sections and revoluble independently thereof, object-bearing means demountably carried on said sleeve and rotatable therewith, said sectional shaft resting in a bearing on the base, an upper bearing demountably held by said frame-work, and means for rotating said sleeve and said sectional shaft in opposite 60 65 directions. 70

3. A toy comprising a base, an upwardly projecting frame, a rotatable shaft, said shaft comprising a plurality of complementary demountable sections, object-bearing means demountably carried by and rotatable with one of said sections, a sleeve demountably positioned on one of said sections and revoluble independently thereof, object-bearing means demountably carried on said sleeve and rotatable therewith, a bearing on the base in which the shaft end rests, a member apertured to form an upper bearing for said sectional shaft, a plurality of bars demountably engaging said bearing member, 80 85 said bars being secured to said frame whereby said upper bearing is supported, and means for rotating said sleeve and said sectional shaft in opposite directions.

In testimony whereof, I have signed my name to this specification.

SAME PATERNO.
